UNITED STATES PATENT OFFICE.

JACOB SICKLER, OF OTTERBEIN, AND EDWARD E. SICKLER, OF INDIANAPOLIS, INDIANA.

SULKY-PLOW.

SPECIFICATION forming part of Letters Patent No. 315,563, dated April 14, 1885.

Application filed July 21, 1884. (No model.)

To all whom it may concern:

Be it known that we, JACOB SICKLER and EDWARD E. SICKLER, of Otterbein, in the county of Benton and State of Indiana, and of Indianapolis, in the county of Marion and State of Indiana, respectively, have invented certain new and useful Improvements in Sulky-Plows; and we do hereby declare the following to be a full, clear, and exact description of our invention, such as will enable others skilled in the art to which it pertains to make and use it, reference being had to the accompanying drawings, which form a part of this specification.

15 Our invention relates to an improvement in sulky-plows.

The invention consists in improvements in sulky-plows, which will first be described, and then pointed out in the claims.

20 In the accompanying drawings, Figure 1 shows a perspective view of our improved sulky-plow. Figs. 2 to 17 show detail views of each part in perspective.

25 *a* is a main casting, having two bearings *con* forming to the curve of the beam, to which it is secured by two clamps, *b b*. The rear end of casting *a* forms a long vertical bearing for swivel-standard *c*, carrying the axle for wheel *d*. Upon the upper end of swivel-standard *c* is pinned a cogged segment, *e*, which is operated by a corresponding segment on the short end of lock-lever *f*. Upon the rear end of casting *a* an ear, *g*, is raised, forming a fulcrum for lever *f*. Upon the top of ear *g* is fixed an adjustable stop, *h*, fitted for the bolt on lever *f*. Spring-lock on lever *f* holds the rear wheel rigid at the will of the operator. The rear wheel, *d*, is inclined to land in such manner as to equalize the vertical and lateral pressure on its axle. The forward end of the plow-beam is made separate from the rear section, and is bolted rigidly to the long spring-catch lever *i*. The forward end of rear section of beam is pivoted in lever *i*. An adjustable rack-segment, *j*, is secured upon the forward end of casting *a*, which receives the spring-bolt on lever *i*, holding lever *i* at any point desired by the operator, thus regulating the depth of furrow. Main frame *k* is carried by the tongue, and is at-

tached by its forward arm through link *l* to the 50 forward end of the beam. The rear arm of frame *k* rests upon the upper side of the beam, and is secured to the main casting *a* by two stirrups, *m m*, in which it has an oscillating motion, and by which the plow is leveled. A 55 seat-lever, *n*, is fulcrumed upon rear arm of frame *k*, and is held in place by two eyes—one at each end of its bearing on rear arm of *k*. The forward arm, *o*, of seat-lever *n* is extended forward parallel to the beam, and passes under 60 a roller attached to lever *i* a short distance to the rear of beam-joint. The weight of the operator thus relieves the lever of the downdraft of the plow, and doubles his power in lifting the plow from the ground. An adjustable 65 arm, *p*, is attached to main frame *k* by means of a surface fitting the outside surface of frame *k*, and two hooks, which grasp the lower edge of frame *k*, and is held in place by a bolt passing through main frame and end of said 70 arm. Upon the outer end of arm *p* is fixed an adjustable block, *q*, which carries an inverted swivel-standard for the forward wheel, *r*, and the rear of which is formed into a bearing, *s*, that corresponds to and moves upon a bearing which is fixed upon the rear of the swivel-sleeve *t*, which is attached to the axle of wheel *r*. Said bearings are so constructed that they will permit wheel *r* to move freely, and at the same time to prevent it from turning at too 75 great an angle when the plow is thrust sideways by passing over an obstruction.

The operation is as follows: The team is harnessed to the forward end of the beam, and the adjustments are identical with those of the 80 ordinary "walking-plow." The operator places spring-bolt on lever *f* in its notch. He then depresses the lever *i* and starts the team, and the plow will enter the ground. By manipulating lever *f* the plow may be forced 85 in any desired direction. Upon reaching the end of the furrow, if the operator desires to turn the plow in the ground, he depresses lever *i* and loosens the spring-bolt on lever *f*, and the team will turn the plow in the ground without 90 difficulty. As the team starts forward, lever *f* is brought back to its notch, and lever *i* is 95 adjusted to the proper depth. If the operator

chooses to turn without plowing, he has only to lift the plow from the ground with lever *i* and loosen spring-lock on lever *f*, when by manipulating lever *f* the plow may be brought 5 into proper position without driving the team beyond the furrow on the opposite side of the plowed land, as is usually necessary in operating sulky-plows.

Having fully described our invention, what 10 we claim as new and valuable, and desire to secure by Letters Patent, is—

1. In a sulky-plow, the combination, with main frame *k* and the tongue, of caster-wheels *d* and *r*, swiveled thereto, and the lever *f*, acting upon the swivel-standard of the rear wheel, *d*, whereby the operator may move the plow in any desired direction, substantially as shown and described.

2. In a sulky-plow, the combination, with 20 main frame *k* and the tongue, and with caster-wheels *d* and *r*, the latter having a swivel-standard adjustable as to width and height, of the swivel-standard *c* of wheel *d*, and the lever *f*, operating to reciprocate said standard *c* by 25 suitable connections, whereby the operator may allow wheel *d* to turn in the furrow, and permit the plow to turn in the ground without

strain of wheel or plow, substantially as shown and described.

3. The combination, with main frame *k*, the 30 tongue, and caster-wheels *d* and *r*, of a plow-beam having a joint therein, and a hand-lever rigidly secured to the front section of said plow-beam, whereby the depth of furrow may be regulated, substantially as shown and 35 described.

4. In a sulky-plow, the combination, with frame *k*, the jointed plow-beam, and the caster-wheels *d* and *r*, of the seat-lever *n*, fulcrumed upon the main frame and provided with the 40 forward arm, *o*, connected to the hand-lever, and the rear arm carrying the seat to the rear of the line of support between caster-wheels *d* and *r*, whereby the weight of the seat and operator will counteract the downdraft, substantially as shown and described. 45

In testimony that we claim the foregoing we have hereunto set our hands this 18th day of July, 1884.

JACOB SICKLER.
EDWARD E. SICKLER.
